G. R. GUILD.

RELAY.

APPLICATION FILED SEPT. 26, 1919.

1,382,356.

Patented June 21, 1921.

UNITED STATES PATENT OFFICE.

GEORGE R. GUILD, OF THE UNITED STATES ARMY, ASSIGNOR OF ONE-HALF TO C. T. PAYTON, OF ST. LOUIS, MISSOURI.

RELAY.

1,382,356.

Specification of Letters Patent. Patented June 21, 1921.

Application filed September 26, 1919. Serial No. 326,518.

To all whom it may concern:

Be it known that I, GEORGE R. GUILD, a citizen of the United States and an officer of the United States Army, stationed at 5 Baltimore, Maryland, have invented a certain new and useful Improvement in Relays, of which the following is a full, clear, and exact description, such as will enable others skilled in the art to which it appertains to make and use the same, reference being had to the accompanying drawings, forming part of this specification.

My invention relates to new and useful improvements in relays, and particularly 15 the types of relays used in connection with the electrical circuits of practically all forms of signaling systems and more particularly those signaling systems utilized in connection with railways for the guidance and control of trains.

My present invention is an improvement upon the relay disclosed in United States Letters Patent No. 1,305,092, issued May 27, 1919 to me and my assignee, C. T. Payton.

The principal objects of my present invention are, to generally improve upon and simplify the construction of the relay disclosed in my patent aforesaid; to materially 30 increase the efficiency of this particular type of relay; and to provide a relay which is relatively simple in construction and operation, applicable for a wide variety of uses, comprising but few operating parts, and 35 said relay being positive in operation and effective in performing its intended functions.

With the foregoing and other objects in view, my invention consists in certain novel 40 features of construction and arrangement of parts, hereinafter more fully described, and claimed, and illustrated in the accompanying drawings, in which—

Figure 1 is a diagrammatic view of a relay 45 constructed in accordance with my invention and showing the circuits and connections between said relay and a section of a railway track and signal lamps.

Fig. 2 is a cross sectional view taken approximately through the center of the relay 50 and showing the relative positions of the operating parts within the relay housing.

Figs. 3 and 4 are diagrammatic views of the relay and the circuits associated therewith and with arrows showing the travel of 55

the current through the various circuits as will occur under different conditions.

Fig. 5 is a diagrammatic view showing the means utilized for connecting the coils of the relay to the sections of the track rail 60 through secondary relays and with the parts of the broken rail connected by an impedance bond.

Referring by numerals to the accompanying drawings, which illustrate a practical 65 embodiment of my invention, 10 designates a housing of suitable size and form, in the lower portion of which are mounted four coils or solenoids 10, 11, 12, and 13, the same being disposed in pairs with the coil 11 directly opposite the coil 10 and the coil 13 opposite to the coil 12. Arranged within the housing 10 above these coils is a horizontally disposed partition 13 in which is formed a centrally arranged aperture 14.

Journaled in suitable bearings that are arranged on the top and bottom walls of the housing is a shaft 15 which passes through the aperture 14 and carried by the lower portion of this shaft is an armature 16, the 80 end portions of which are positioned between the cores of the coils or solenoids.

A relatively light helical spring 17 has one end secured to shaft 15 and the other end to the partition 13, said spring being 85 intended to hold the shaft 15 in position so that the armature 16 normally occupies a neutral or intermediate position between the cores of the solenoids or the position as illustrated in Figs. 1 and 2.

Carried by shaft 15 and disposed within housing 10 above the partition 13 is a disk 18 of suitable insulating material and arranged on the periphery thereof or immediately adjacent to its peripheral edge is a 95 pair of contact members 19 and 20. Arranged on the periphery of said disk at diametrically opposite points from said contact members 19 and 20 are contact members 21 and 22, the same being suitably spaced 100 apart.

Arranged on the partition 13 and positioned so as to be engaged by contact member 19 are three contact members 23, 24 and 25, and a pair of similar contact members 105 26 and 27 are arranged on the partition 13 in position to be engaged by the contact member 20. A series of three contact members 28, 29 and 30 are arranged on partition 13 so as to be engaged by contact mem- 110

ber 21, and a corresponding series of three contact members 31, 32 and 33 are positioned on the partition and adapted to be engaged by contact member 22.

5 Located at a suitable point adjacent to the railway track with which my improved relay is associated, is a red lamp 34, a green lamp 35 and a yellow lamp 36, all of said lamps receiving current through line 37 10 from a battery 38. Leading from red lamp 34 to contact member 27 is a conductor 39 and leading from green lamp to contact member 23 is a conductor 40. Leading from yellow lamp 36 to contact member 35 is a 15 conductor 41. Leading from a battery 42 to the coils 10 and 11 is a conductor 43 and leading from the opposite side of said battery to the continuous track rail 44 is a conductor 45. Connecting coils 11 and 12 is a 20 conductor 46 and connecting coils 10 and 13 is a conductor 47. Leading from coil 12 to contact member 38 is a conductor 48, and connecting coil 13 with contact member 31 is a conductor 49. Leading from contact 25 member 29 to one of the sections 50 of the broken or divided track rail is a conductor 51 and leading from the latter to contact member 31 is a conductor 52. Leading from conductor 32 to the adjacent section 53 of 30 the broken or divided track rail is a conductor 54 and leading from the latter to contact member 30 is a conductor 55.

Thus by my improved arrangement it will be seen that coils or solenoids 10 and 13 are 35 in series and likewise coils or solenoids 11 and 12 are in series and that under normal conditions or with the track open, both sets of coils are ready to act upon the armature 16 and consequently effect a partial rotation 40 of shaft 15 and the disk 18 carried thereby. Further, the coils 11 and 12 are in series with that block or portion of the track which includes the rail section 50 so long as 45 this particular block or section of the track is clear. Likewise coils 10 and 13 are in series with that portion or block of the track in which rail section 53 is located so long as this portion or block is clear.

In the event that coils 11 and 12 are 50 energized by the closing of the circuit between continuous rail 44 and rail section 50, disk 18 will be turned clockwise, thereby cutting coils 10 and 13 out of circuit, but at the same time, the block or portion of the 55 track in which rail section 53 is located is in circuit with coils 11 and 12. These conditions will be more readily understood by reference to Figs. 3 and 4, for the wheels and axles of a locomotive or car entering 60 the block in which rail section 50 is located will close the circuit between said rail section 50 and the continuous rail 44, which circuit includes battery 42, conductor 43, coil 11, conductor 46, coil 12, conductor 48, contact member 28, contact member 21, contact

member 29, conductor 51, rail section 50, truck X, continuous rail 44, and conductor 45 to battery. As this circuit is closed, the coils 11 and 12 would be energized, thereby attracting the ends of armature 16 so that 70 the same is shifted to partially rotate shaft 15 and disk 18 clockwise. Previous to this clockwise movement of the disk 18 or while the latter occupies its normal position, contact member 19 is in engagement with contact members 23 and 24, thereby closing the circuit through conductor 37, battery 38, and conductor 40 to the green lamp 35 so that while the relay is in normal condition and the track clear, said green lamp is 75 so lighted.

When disk 18 is moved clockwise as just described contact member 19 is moved to a position out of engagement with contact members 23 and 24, and contact member 20 80 is moved into position to engage contact members 26 and 27, and as a result, the circuit in which the green lamp is located is opened, and the circuit in which the red lamp 34 is located is closed. Thus the red 90 lamp will burn to indicate the presence of a locomotive or train on the block controlled by the relay, and this condition will prevail with the red lamp burning as long as the locomotive or train is on this particular 95 block.

The passage of the truck X across the block between rail sections 50 and 53 in no wise affects the position of the parts of the relay or the burning of the red lamp and 100 after said truck passes onto that portion of the block in which rail 53 is located, the current instead of passing from contact member 29 to rail section 50 will pass from contact member 30 through conductors 55 and 54 to 105 rail section 53, as illustrated by the heavy circuit-indicating lines in Fig. 4.

In the event that a locomotive or car enters the ends of the block in which rail section 53 is located, the circuit between said 110 last mentioned rail section and continuous rail 44 will be closed through the trucks of said locomotive or train, and as a result, solenoids 10 and 13 will be energized to attract the ends of armature 16 and rotate shaft 15 115 and disk 18 anti-clockwise. As this operation takes place, contact member 19 moves into engagement with contact members 24 and 25, thereby closing the circuit in which yellow lamp 36 is located, causing the same 120 to burn, thereby indicating the presence of a locomotive or car on this portion of the block, and as disk 18 is thus rotated, contact member 21 will move out of engagement with contact members 28 and 29, and contact 125 member 22 will move into engagement with the three contact members 31, 32 and 33, with the result that the proper signal will be held during the entire passage of the car or train through the block notwithstanding the 130

fact that such car or train crosses the break between the rail sections 58 and 53.

Obviously, during the passage of a locomotive or train off the block controlled by 5 the relay, the circuit in which the coils are located will be broken, and as said coils are deenergized, the spring 17 will act to return the shaft 15 and disk 18 to normal position under which conditions the green lamp 35 10 will burn to indicate an open or clear block.

Instead of directly connecting the coils of the relay to the track rails as heretofore described, the relay may be operated by means of secondary track relays such as 60 15 either of direct or alternating current design. (See Fig. 5). Further, if desired, a source of alternating current may be used instead of direct current and an impedance bond, as illustrated in Fig. 5, may be used 20 between the sections of the broken or open track rail.

A relay and signal system of my improved construction is relatively simple, positive in action, and very efficient in use.

25 Practically the same form of relay can be advantageously used in connection with other systems of block signal and relay train control, it only being necessary to preserve the general arrangement of the solenoids and 30 the stationary and moving contact members. If desired, the coils 11 and 12 may be wired in multiple with that portion of the block in which rail section 50 is located, and likewise, if desired, the coils 10 and 13 may be 35 wired in multiple with that portion of the block in which rail section 53 is located.

It will be readily understood that minor changes in the size, form and construction of the various parts of my improved relay and 40 signal system may be made and substituted for those herein shown and described, without departing from the spirit of my invention, the scope of which is set forth in the appended claims.

45 I claim:

1. The combination with a railway track having a continuous rail and a broken or open rail, of a relay comprising four solenoids, two of which are oppositely disposed 50 and are connected in series with one of the sections of the broken or open rail, the other two solenoids being oppositely disposed and connected in series with the other section of the broken rail, and an armature pivotally mounted between said solenoids and adapted 55 to be attracted by either pair of connected members of said solenoids when the circuit between the continuous rail and either section of the broken rail is closed.

60 2. The combination with a railway track having a continuous rail and a broken or open rail, of a relay comprising four solenoids, two of which are oppositely disposed and are connected in series with one of the 65 sections of the broken or open rail, the other

two solenoids being oppositely disposed and connected in series with the other section of the broken rail, an armature pivotally mounted between said solenoids and adapted to be attracted by either pair of connected 70 members of said solenoids when the circuit between the continuous rail and either section of the broken rail is closed, a plurality of lamp circuits, a member carried by the armature and movable therewith, and means 75 on said member for closing said lamp circuits.

3. The combination with a section of railway track having a continuous rail and an open or broken rail, of a pair of solenoids 80 oppositely disposed and in circuit with said continuous rail and one of the sections of the broken rail, a second pair of solenoids oppositely disposed and in circuit with the continuous rail and the other section of the 85 broken rail, and an armature pivotally mounted between said solenoids and adapted to be actuated upon the closing of either one of the circuits in which said solenoids are located. 90

4. The combination with a section of railway track having a continuous rail and an open or broken rail, of a pair of solenoids oppositely disposed and in circuit with said continuous rail and one of the sections of the 95 broken rail, a second pair of solenoids oppositely disposed and in circuit with the continuous rail and the other sections of the broken rail, an armature pivotally mounted between said solenoids and adapted to be 100 actuated upon the closing of either one of the circuits in which said solenoids are located, a plurality of lamp circuits, and means controlled by the armature for closing certain of said lamp circuits upon the 105 closing of the circuits in which the solenoids are located.

5. The combination with a section of railway track having a continuous rail and an open or broken rail, of connected oppositely 110 disposed solenoids, one pair of said solenoids being connected to the continuous rail, connections including contact members between the other pair of solenoids and the section of the broken rail, and means adapted to be 115 actuated by said solenoids when energized for closing the circuits through said contact members.

6. The combination with a section of railway track having a continuous rail and an 120 open or broken rail, of connected oppositely disposed solenoids, one pair of said solenoids being connected to the continuous rail, connections including contact members between the pair of solenoids and the section 125 of the broken rail, means adapted to be actuated by said solenoids when energized for closing the circuits through said contact members, and a plurality of lamp circuits which are adapted to be closed when the cir- 130

cuit between the continuous rail and either section of the broken rail is closed.

7. In combination with a railway track having a continuous rail and a broken or open rail, a relay comprising an armature, a pair of solenoids connected in series with one of the sections of the broken rail, the members of said pair of solenoids being on opposite sides of the armature and adapted to simultaneously attract the opposite ends thereof when energized, and a second pair

of solenoids connected in series with another section of the broken rail, each member of said second pair of solenoids being opposite the adjacent member of the first pair, the members of said second pair of solenoids being adapted to simultaneously attract the opposite ends of the armature when energized.

In testimony whereof I hereunto affix my signature this 28th day of August, 1919.

GEORGE R. GUILD.
